UNITED STATES PATENT OFFICE.

HYNEK BREUER, OF NEW PRAGUE, MINNESOTA.

WINDOW-SILL.

SPECIFICATION forming part of Letters Patent No. 376,940, dated January 24, 1888.

Application filed October 24, 1887. Serial No. 253,198. (No model.)

To all whom it may concern:

Be it known that I, HYNEK BREUER, of New Prague, in the county of Scott and State of Minnesota, have invented a new and Improved 5 Window-Sill, of which the following is a full, clear, and exact description.

My invention relates to window-sills for buildings, and has for its object to provide a cheap, strong, durable sill which, when set in place, will present a neat finish, and will effectually exclude rain, snow, or dust from the building, and will also protect the wall of the building, and thereby promote the durability of a brick, stone, or wooden structure in which 15 the sill is used.

The invention consists in certain novel features of construction of the window-sill, all as hereinafter described and claimed.

Reference is to be had to the accompanying 20 drawings, forming a part of this specification, in which similar letters of reference indicate corresponding parts in all the figures.

Figure 1 is a front view of a portion of a 25 wall around a window-opening and with my improved window-sill applied as in use. Fig. 2 is a vertical sectional view taken on the line xx , Fig. 1. Fig. 3 is a perspective view of the sill. Figs. 4 and 5 are cross-sections of sills of different molded forms, and Figs. 6 and 7 30 are respectively a plan and front view of a sill adapted for use with iron or metal front buildings.

I will first describe the sill shown in Figs. 1 to 5, inclusive, of the drawings, and which is 35 adapted more particularly for use in brick or stone buildings, but which may be used to advantage in wooden structures.

This window-sill is formed with a ledge or 40 plate, A, which rests on the wall of a building, and an ornamental or molded front pendent portion, B, which is preferably cast or formed with the plate A and projects below said plate at the face of the wall of the building. At its rear or inner edge the sill-plate A is 45 provided with an upwardly-projecting lip or flange, C, which enters a groove, d, made in the under side of the sill D of a window-frame, E, built into the wall. At the angle between the sill-plate A and the front molded part, B, 50 of the sill a number of webs or flanges, a, are

cast or fastened to serve as braces or binders to assure proper strength of the sill, and the number of these bracing-webs a will vary with the length and thickness of the sill.

The sill-plate A is of sufficient length to extend four inches (more or less) into the wall F of the building at each side of the window-frame opening, and the width of said plate A is sufficient to cause the window-frame sill D to overlap it an inch or two outside of the engaging lip and groove C d of the sill and window-frame, as will appear from Figs. 1 and 2 of the drawings.

It is obvious that the above-described window-sill may be very easily set in place, and 65 that when in position its lip or flange C will prevent the beating of rain or snow storms onto the wall of the building back of the sill, and thus will protect the wall and promote its durability, and the flange or lip will also exclude wind and dust from the inside of the 70 building. Furthermore, the front pendent plate or molding, B, while giving the window a neatly-finished appearance, will at the same time effectually prevent the beating of storms 75 under the front of the main sill-plate A, and will thus protect the wall, and water running off the plate A will flow down onto the molded plate B and will drop from its face at points b; hence the wall will not be water-soaked to an 80 injurious extent.

When the sill is to be used for iron buildings, the top plate, A, having the pendent front molded plate, B, will be provided at opposite ends with upwardly-projecting flanges 85 G G, which may have any general form, either straight, curved, or angular, to conform to the inside face or shape of pillars or posts H, set at the sides of the window-opening. These pillars H, which will be bolted to the sill-flanges G, are indicated in dotted lines in Fig. 6 of the drawings, from which and Fig. 7 the construction of the modified form of sill for iron buildings will be clearly understood.

I purpose making the sill in one piece of 95 metal cast in the ordinary way, in iron or steel, thus giving ample strength and great durability to the sills and allowing their manufacture at a low cost; but the sill may be made of one or more pieces of any suitable material. 100

Having thus described my invention, what I claim as new, and desire to secure by Letters Patent, is—

1. As an improved article of manufacture, a window-sill made with a main plate, A, and a front pendent wall plate or molding, B, and said plate A provided with a lip or flange, C, at its inner edge and adapted to a groove in a window-frame, substantially as herein set forth.
- 10 2. As an improved article of manufacture, a window-sill made with a main plate, A, and a front pendent wall plate or molding, B, and web braces *a* at the angle of said plates A, B,

and said plate A provided with a lip or flange, C, at its inner edge, substantially as described, 15 for the purposes set forth.

3. A window-sill made with a main plate, A, and a front pendent wall plate or molding, B, and said plate A provided with upwardly-projecting flanges G, to which the window-pillars 20 may be bolted, substantially as herein set forth.

HYNEK BREUER.
